INSULATION

Filed Aug. 26, 1929

INVENTOR
Frank R. Leslie

BY *John L. Johnson*
ATTORNEY

UNITED STATES PATENT OFFICE

FRANK R. LESLIE, OF WHITE BEAR LAKE, MINNESOTA

INSULATION

Application filed August 26, 1929. Serial No. 388,371.

My invention relates to improvements in insulation adapted particularly to be supported between studdings or beams, as in house construction.

5 An object of my invention is to provide an insulation made of corrugated board, with a plurality of boards to form intermediate air spaces, so put together and constructed that they may be delivered in a flat 10 condition, but which in use may be conveniently fitted between the studdings to form connected insulating boards with intermediate air space.

I am aware that it is old to construct an 15 insulation of sheets of corrugated board to fit between studdings and with air spaces between the sheets, but where such form of insulation has been used that is already built up ready for insertion between the studdings 20 and the edges of the board secured together, there is an inconvenience and expense in connection with shipping and handling this insulation. As the sheets are not in a flat 25 position, there is a lack of adjustability in fitting the material between the studdings, and other objections, not existing in my construction.

These and other features of my invention 30 will be more specifically set forth in the following description and the accompanying drawings, wherein:

Figure 1 is a face view of my invention made up of two sheets of corrugated board before the sheets have been bent as in use.

35 Figure 2 is a section on line 2—2 of Figure 1.

Figure 3 is a top view of my invention shown fitted between building studdings; and

40 Figure 4 is an edge view of my invention shown partially bent for placement in use and illustrating its adaptability to variations in widths of supporting studs.

Referring to the drawings in detail, and 45 using two sheets of corrugated board, I make the sheet 2, which constitutes the rear sheet in use, longer than the superimposed sheet 3. The sheet 2 is formed with bending lines 4 some distance inside of each edge. The 50 sheet 3 is similarly formed with bending

lines 5 closer to the edge of the sheet 3 than the bending lines 4 are to the edge of the sheet 2. The two sheets are placed together with adjacent edges in line and secured as by stitching 6 between the bending lines and 55 the adjacent edges of the sheets, the edges of which are in alinement. When the sheets are thus fastened together, the opposite end of the sheet 3 lies some distance inside of the adjacent edge of the sheet 2 and those 60 edges are left unsecured. When thus secured together, as shown in Figure 2, the bending line 5 upon the stitched side of the sheet 3 will stand outside of the bending line 4 of the sheet 2 and upon the unconnected portion of the sheets. The bending line 5 of sheet 3 will stand inside the bending line 4 of the sheet 2. When the sheets are 65 secured together as shown in Figure 2, they are ready for shipment as flat material. 70 When it is desired to secure the sheets in insulating position between the studs 7, the edges are bent as shown in Figure 3 into alinement with each other and with the studs, and then fastened as by fastening means 8 to the studs. The fact that the 75 sheets are made up in the relative position and arrangement shown in Figure 3, permits their being bent to hold the sheets in separated position, as shown in Figure 3, and also by reason of the fact that when placed in position, one side of the sheets is unconnected, there is a certain latitude permitted in bending away from a true right-angled bending, as indicated in Figure 4, to permit 80 an accommodation to slight variations in distances between studs, a result not possible where the sheets of corrugated board are built up in a thoroughly secured position along both edges, ready for insertion. 85

A particular advantage of my invention is the fact that the material may be shipped in a flat condition, making shipment much more convenient and satisfactory, and making it much easier to protect the material in shipment and in handling.

I claim:

1. An insulation consisting of a plurality of sheets of superimposed board of varying widths and with the edges of the sheets on 100

- one side in alinement when positioned together, means for securing the sheets together along the aligning edges, with the sheets unsecured at the opposite edges, and
5 bending lines upon the sheets varying distances apart upon adjacent sheets, whereby the edges of the sheets may be bent into alinement holding the central portions of the sheets separated.
- 10 2. An insulation consisting of a sheet of corrugated board, a superimposed similar sheet of shorter width, the two sheets being placed together with the edges upon one side in substantial alinement, means for securing together the aligning edges of the sheets, leaving the other edges of the sheets unsecured, bending lines upon the wider sheet a certain distance inside each edge, and similar bending lines upon the narrower sheet, positioned inside the edges a less distance away than the bending line upon the wider sheet, for the purpose set forth.
- 15 In testimony whereof I affix my signature.
